COMBINED BAIT AND LURE

Karl R. Larson, Aitkin, Minn.

Application April 16, 1948, Serial No. 145,753

Term of patent 14 years

(Cl. D31—4)

To all whom it may concern:

Be it known, that I, Karl R. Larson, a citizen of the United States, residing at Aitkin, in the county of Aitkin and State of Minnesota, have invented a new, original, and ornamental Design for Combined Bait and Lure, of which the following is a specification, reference being had to the accompanying drawing, forming part thereof.

Figure 1 is a top plan view of a combined bait and lure showing my new design; and

Figure 2 is a side elevational view of the same.

The essential feature of my design resides in the bait element shown in full lines, one surface of which is spotted as shown.

I claim:

The ornamental design for a combined bait and lure, as shown and described.

KARL R. LARSON.
